UNITED STATES PATENT OFFICE.

BENJAMIN F. FIELD AND ELI P. CLARK, OF LOS ANGELES, CALIFORNIA.

FEED-WATER HEATER AND PURIFIER.

SPECIFICATION forming part of Letters Patent No. 502,085, dated July 25, 1893.

Application filed November 23, 1892. Serial No. 452,895. (No model.)

To all whom it may concern:

Be it known that we, BENJAMIN F. FIELD and ELI P. CLARK, citizens of the United States, residing at Los Angeles, in the county 5 of Los Angeles and State of California, have invented a new and useful Feed-Water Heater and Purifier, of which the following is a specification.

Our invention is especially adapted for that 10 class of steam generators known as the Stirling boiler, which consists in a series of boilers connected with a heater and mud drum by a series of substantially vertical tubes.

Our invention, however, is applicable to 15 other water tube steam generators, such for instance as that known as the porcupine or Hazleton boiler in which a boiler is set erect in the furnace and the fire is applied to the outside of the boiler. We shall show and de- 20 scribe our invention as applied to the Stirling boiler only, as that will fully illustrate its principle and operation.

One object of our invention is to adapt the 25 heater and purifier for application to the ordinary Stirling boiler after such boiler has been put in place, utilizing the boiler tubes as a portion of the heater and purifier. Viewed in this light our invention comprises certain 30 improvements for the Stirling boiler to form in connection therewith a purifier and heater which will purify and heat the water before it is allowed to enter the steam chamber or boiler proper.

A further object is to provide for the effective and convenient removal of the deposits of 35 sediment which occur in the process of purifying the water.

Our invention comprises an improvement 40 for Stirling boilers consisting in a pipe system arranged within the mud drum and heater and communicating with the feed pipe; a series of tubular connections arranged to connect such pipe system with a series of the vertical tubes of the boiler, and a valve-controlled 45 blow-off communicating with such coil.

It also comprises the combination of a series of steam chambers or boilers; a heater or mud drum arranged below such boilers; systems of tubes communicating between the 50 lower heater or mud drum and the boilers

respectively; a feed-water pipe; a sediment receiving and water-heating coil or pipe-system arranged within the lower heater or mud drum and communicating with the feed-water pipe; a series of tubes leading from such coil 55 and passing upward vertically through the heating furnace and opening into one or more of the boilers; the furnace arranged to heat the boilers, the heater or mud drum, the coil, and said vertical tubes; and a valve controlled 60 blow off communicating with the coil.

Our invention also embraces the combination with the features above mentioned of an auxiliary water-heating pipe-system arranged within the furnace and communicating between the feed-water supply and the sediment receiving and water heating coil or pipe system within the drum, (whereby the water is heated by the heat of the furnace before it enters the coil or system of pipes within the heater or mud drum) and also communicating at one end with the steam boiler and at the other end with the blow-off. This last feature may be used or not according to the 70 peculiarities of the circumstances, in some 75 instances being desirable and in others less so.

The accompanying drawings illustrate our invention.

Figure 1 is a vertical section transverse the heating drum and steam boiler and the sediment coil or pipe system, and longitudinal the vertical discharge tubes leading from such coil into the primary boiler. The removable extension of such vertical tubes is left intact. Fig. 2 is a vertical section looking toward the 80 left on line $x-x$ Fig. 1 cutting longitudinal the primary steam boiler and breaking the heating drum and leaving the sediment coil or pipe system of such drum intact. Fig. 3 is a section on line $y-y$ Fig. 1 looking toward 85 the right and illustrates the auxiliary coil or system arranged to be heated by the direct application of heat within the furnace to heat the water before it enters the pipe system within the lower heater or mud drum. 90

A is the furnace arranged substantially in the manner customary with the Stirling generator.

B, B' and B'' indicate the several steam chambers or boilers proper which are respect- 100

ively connected with the lower heater or mud drum C by the tube systems D, D' and D".

E is the feed water pipe.

F is the supply valve which controls the 5 supply.

G is the blow off and H is the valve which controls the same.

I is the sediment coil or pipe system arranged within the heater or mud drum C and 10 communicating with the feed water pipe E.

I' is the discharge member of the sediment coil and i i are the tubular connections connecting such discharge member with the tubes d of the tube system D. The feed water pipe 15 is connected with a sufficient number of the tubes d of the system which communicates between the heating drum C and the upper steam chamber or boiler proper, to cause the feed water ascending from the sediment coil 20 to pass upward very slowly so that the solids contained therein may subside and deposit within the discharge limb I'. The tubes d thus connected with the sediment coil are arranged to receive the heat of the furnace 25 more directly than other tubes d" of the system; that is to say the tubes d are in front of the tubes d" which are not connected with the sediment coil. This allows the water in the tubes d to become well heated before it 30 enters the steam chamber or boiler B.

It is desirable that the blow off pipes should have their mouths near the surface of the water in the boiler so that the surface impurities will be removed thereby and we therefore provide a series of removable tubular extensions which are respectively provided with a flange e' arranged around the lower end of such tubular extensions which extensions are of such size, respectively, as to fit snugly within 35 their respective pipes d, and are of such length 40 as to extend to near the water line.

The auxiliary heating coil J is arranged in the top part of the furnace near the front wall and passes back and forth through the 45 furnace a sufficient number of turns to cause the water to become heated by the heat of the furnace before entering the sediment coil within the heating drum C.

The object in placing the coil close to the 50 front wall as shown is to utilize the heat at this part of the furnace without detracting from the effect of the furnace upon the boiler proper.

In the drawings the sediment coil is shown 55 connected with eight of the tubes of the front row of the tube system D leaving nine tubes d' of such front row to operate in conjunction with the other tubes d" of the system D to carry on the circulation from the primary 60 boiler B to the heating or mud drum C, from whence it passes to the other boilers B' and B" through the tube systems D' and D" as in the ordinary Stirling boiler.

K indicates the water pipe connecting the 65 boilers B' and B" below the water line and L L' indicate the steam connections between the boilers B and B', and B' and B".

We will now describe the operation of our invention (including the auxiliary coil) beginning when the boilers have been filled with 70 water, the furnace fired, and the steam raised.

The feed water passes through the auxiliary heating coil J thereby becoming heated, and, passing thence into the sediment and heating coil I, it becomes heated to a temperature corresponding substantially to that of the water within the heating or mud drum C. Thence the water passes slowly through the tubular connections i and ascends through the tubes d becoming more highly heated by 75 the direct action of the heat of the furnace. The solids contained within the water are caused to separate from the water by the change in temperature and are allowed to subside into the discharge limb I' of the sediment coil. When sufficient time has elapsed for a deposit of any consequence to occur within the limb I', the blow off valve H is opened; the pressure of the steam in the boilers then forces the water back through the 80 pipes d, tubular connections i, discharge limb I' and sediment coil I and out through the blow off G. When the deposit has thus been removed, the blow off valve is closed and the operation is repeated as before.

N is a supplemental boiler blow off pipe arranged to communicate between the boiler B" and the auxiliary heating coil J so that when the blow off is operated the coil J may also be cleansed. A valve O is arranged to 100 close the pipe N. This valve O is kept closed except when blowing off the mud.

Now, having described our invention, what we claim as new, and desire to secure by Letters Patent, is—

1. The improvement in Stirling boilers set forth consisting in the combination of a pipe system arranged within the mud drum and heater of the boiler and communicating with the feed pipe; a series of tubular connections 110 arranged to connect such pipe system with a series of the vertical tubes of the boiler, and a valve-controlled blow off communicating with such coil.

2. The combination set forth of a steam 115 boiler; a drum arranged below such boiler; a system of tubes communicating between the drum and the boiler; a feed water pipe; a sediment receiving coil or pipe system arranged within the lower drum and communicating with the feed water pipe; a series of tubes leading from such coil and passing upward through the heating furnace and opening into the boiler; the furnace arranged to heat the boiler, the drum, the coil and the 120 tubes, and a valve-controlled blow off communicating with the coil.

3. The combination set forth of the boiler; the feed pipe; the coil communicating with the feed pipe; the vertical tubes communicating between the coil and the boiler; the valve-controlled blow off communicating with the coil and the valve-controlled supplemental 130 blow off pipe arranged to communicate be-

tween the boiler and the coil, and the furnace arranged to heat the boiler and the coil.

4. The combination set forth of the steam boiler; a drum arranged below such boiler; a system of tubes communicating between the drum and the boiler; a feed water pipe; a sediment receiving coil or pipe system arranged within the lower drum and communicating with the feed water pipe; a series of tubes leading from such coil and passing upward through the heating furnace and opening into the boiler; the auxiliary heating coil arranged in the furnace and communicating

with the sediment coil within the heating drum; a supplemental valve-controlled blow-off pipe arranged to communicate between the boiler and the auxiliary heating coil; the furnace arranged to heat the boiler, the coil, the drum and the tubes, and a valve-controlled blow-off communicating with the coils. 15 20
